(57) **CLAIM**

The ornamental design for a pole extrusion as shown and described.

DESCRIPTION

FIG. 1 is a front top perspective view of the pole extrusion. FIG. 2 is a rear bottom perspective view thereof.

FIG. 3 is a left side elevation view thereof.

FIG. 4 is a right side elevation view thereof.

FIG. 5 is a front elevation view thereof.

FIG. 6 is a rear elevation view thereof.

FIG. 7 is a top plan view thereof; and,

FIG. 8 is a bottom plan view thereof.

The pole extrusion is shown with a symbolic break in its length. The appearance of any portion of the pole extrusion between the jagged break lines forms no part of the claimed design.
